DESIGN FOR A HANDBAG

Louis J. Coblenz, New York, N. Y.

Application September 9, 1940, Serial No. 94,885

Term of patent 3½ years

To all whom it may concern:

Be it known that I, Louis J. Coblenz, a citizen of the United States of America, residing in New York, county of New York and State of New York, have invented a new, original, and ornamental Design for a Handbag, of which the following is a specification, reference being had to the accompanying drawing, forming part thereof.

Fig. 1 is a perspective view of a handbag showing my new design.

Fig. 2 is an opposite view thereof.

Fig. 3 is a bottom plan view thereof.

I claim:

The ornamental design for a handbag, as shown.

LOUIS J. COBLENTZ.
